UNITED STATES PATENT OFFICE.

HYMAN MAIMIN, OF NEW YORK, N. Y., ASSIGNOR TO H. MAIMIN CO., INC., A CORPORATION OF NEW YORK.

FABRIC-CUTTING MACHINE.

1,305,480

Specification of Letters Patent. Patented June 3, 1919.

Application filed March 22, 1917. Serial No. 156,687.

To all whom it may concern:

Be it known that I, HYMAN MAIMIN, a citizen of the United States, residing at New York city, in the county of New York, State of New York, have invented certain new and useful Improvements in Fabric-Cutting Machines; and I do hereby declare the following to be a full, clear, and exact description of the invention, such as will enable others skilled in the art to which it applies to make and use the same.

This invention relates to the construction of cloth-cutting machines of the reciprocating knife type, and the association therewith of knife-sharpening means, for the purpose of facilitating and improving the knife-sharpening operation, with particular reference to the sharpening of the chopping edge, commonly employed at the lower end of reciprocating knives.

Although it is a relatively simple matter to sharpen the vertical slicing edge of these knives without removing the knife from the machine, it has been the common practice to remove the knife from the machine for the purpose of sharpening the chopping edge at its lower end. In United States Patent Number 1,186,488, granted to me on June 6, 1916, I show a construction of cloth-cutting machine and an arrangement of knife-sharpening apparatus which permits the convenient sharpening of this chopping edge without removing the knife from the machine, provision being made for producing a relative movement between the knife and its sheath on the standard for the purpose of exposing the lower chopping edge of the knife, and a sharpening apparatus being provided for effecting the sharpening after the edge is so exposed.

In that patent there is likewise disclosed an arrangement in which the sharpening apparatus is attached to the machine in such a way that it can be swung into and out of the sharpening relation to the edge of the knife, and connections are provided between the attachment and the motor casing which carries the knife so that when the sharpening attachment is swung into its sharpening position it automatically moves the knife out of its sheath in the standard to expose the lower edge for sharpening.

The present invention constitutes an improvement of the construction and mode of operation of machines of that general character, and includes an improvement in the action of the sharpening apparatus, and also an improvement in the mechanism by which the movement of the sharpening apparatus into its effective position automatically brings about the movement of the knife to expose its lower cutting edge for sharpening. In the specific apparatus disclosed in that patent, the arrangement is such that the knife is brought forward by a movement of translation to expose the cutting portion of the lower edge, but the entire rear, non-cutting edge of the knife-blade remains within the sheath and is held thereby from lateral movement. I have discovered that better sharpening results are attained if there is imparted to the knife a swinging movement of such a character as to protrude the lower edge far enough substantially to clear the sheath, while the blade of the knife remains to a greater degree within the embrace of the sheath. In this way, the lower edge of the knife-blade is free to bend under the action of the sharpening stones, while the length of the blade is securely held by the sheath and by the knife-holding mechanism within the motor casing. In accordance with the present invention, furthermore, the specific form of apparatus for carrying the sharpening means is more simple and more effective than the corresponding apparatus in the patent referred to.

I have shown, in the accompanying drawings, the preferred embodiment of the invention, and likewise an improved sharpening apparatus, but the improved sharpening apparatus forms no part of the present invention, and is claimed in a co-pending application Serial No. 161,196 filed by one Henry B. Batjer on April 11, 1917.

In the drawings, Figures 1 and 2 are side elevations, and Figs. 3 and 4 are front elevations of a cloth-cutting machine constructed in accordance with the invention. Figs. 1 and 3 showing the sharpening attachment in retracted position, and Figs. 2 and 4 showing it in operative position; Figs. 5 and 6 are sectional views taken, respectively, on the lines 5-5 and 6-6 of Fig. 2; and Figs. 7, 8, 9 and 10 are detail views particularly illustrating the knife-sharpening apparatus which forms the subject matter of another application, Figs. 7 and 8 being sec-

tional views taken, respectively, on the line 7—7 of Fig. 4, and on the line 8—8 of Fig. 2, and Figs. 9 and 10 showing details of construction.

5 By reference to Figs. 1, 2, 3 and 4, it will be seen that the foot-plate 12 of the machine is provided with the usual ramp 13, so that the foot-plate may be advanced under the fabric to be cut, and the standard 14, rising 10 from the foot-plate, has the usual sheath for the knife 17 provided with the front slicing edge 16 and the bottom chopping edge 15. The machine has the usual motor 18 and casing 19 which carries the knife and 15 incases the knife-driving connections which may be of any suitable character known to the art, and which are not here illustrated.

The upper end 14^a of the standard 14 is preferably squared, as indicated in Fig. 5, 20 and projects within an enlarged recess 22 in the casing 19. A bolt 24, having a nut 24^a, extends through the casing and through an enlarged bore 23 in the enlargement 14^a of the standard, thus securing the casing to 25 the standard in such a way as to permit a limited relative movement between the standard and the casing, as illustrated in Fig. 2. It will be seen that the movement is such as to swing the lower end of the 30 knife forward to expose the chopping edge 15, while the knife is held by the casing and its blade is embraced by the sheath in the standard, as shown. This swinging movement is effected by means of a cam- 35 shaft, best illustrated in Fig. 5, and having at one end a cylindrical portion 26 supported in a bearing in the casing 19 and extended in a screw-threaded portion which receives the nut 27 which sets into a recess 28 40 and which is held in place by the screw-cap 27'. On the other end of the cam-shaft is a cylindrical portion 29 journaled in the sleeve of a gear 30 which is locked against rotation in the housing 19 by means of a key. The 45 intermediate portion of the cam-shaft is an eccentric cylinder 25 journaled in the portion 14^a of the standard, the setting of the eccentric being such that when the shaft is rotated, by swinging the knife-sharpening attachment from the position shown in 50 Fig. 1 to the position shown in Fig. 2, the housing will be tipped, with respect to the standard, to project the lower chopping edge of the knife from its sheath.

55 The knife-sharpening apparatus is carried by a vertical portion 31^a of an arm 31 which terminates at its upper end in a yoke 32 embracing a block 33 integral with the cam-shaft and constituting a bearing for 60 an axle 34 on which the yoke 32 is rotatable.

Loose on the shaft 34 between the block 33 and one arm of the yoke 32 is the bevel pinion 40 which meshes with the fixed bevel pinion 30, and the yoke 32 carries a pin 41 65 extending into a slot 42 in the gear 40, so

that the arm 31 has a limited swinging movement with respect to the gear 40. For the purpose of retaining the arm 31 in its elevated position, shown in Figs. 1 and 3, there is secured to the yoke 32, in such manner as to rotate with the yoke on the axle 34, a latch 36 adapted to engage a notch 37 in the standard, and to be held in the extreme position shown in Fig. 1 by the falling tendency of the arm 31. 70

The operation of these parts is as follows. During the cutting operation, the arm 31 stands in the position shown in Figs. 1 and 3, and in this position the pin 41 is in contact with, or close to, the terminal 42^a of 80 the slot 42. To unlatch the arm 31, it is turned slightly in a direction away from the observer in Figs. 1 and 3, until the latch 36 clears the notch 37. Thereupon the arm 31 is turned in a clockwise direction, turning with it the cam-shaft and the eccentric cam 25, and this movement is continued until the casing 19 and the knife carried thereby are brought into the tilted position shown in Fig. 2. During the first part of 90 this movement, the pinion 40, meshing with the pinion 30, is turned on the axle 34 in a clockwise direction as viewed in Fig. 6, until the terminal 42^b of the slot 42 engages the pin 41. This in effect establishes a connection between the gear 40 and the arm 31, so that a further rotation of the arm 31 on the axis of the cam-shaft gives rise to a simultaneous rotation of that arm, driven by the gear 40, on the axle 34, so that the arm, 100 which has theretofore swung in a vertical plane, is automatically swung inward to bring the knife-sharpening devices in line with the knife, as shown in Figs. 2 and 4. When this inward swing of the arm is completed, and sharpening-apparatus is brought directly in line with the knife, the movement is stopped by the engagement of a stop 35 with the side of the casing, as illustrated best in Fig. 4. 105

110 Although I prefer to use the latch 36—37 as shown, it will be understood that the parts may be so tightened that friction alone will hold the arm in its elevated position as shown in Figs. 1 and 3.

The arm 31 carries suitable knife-sharpening apparatus equipped with a pair of sharpening stones, together with mechanism for wiping those stones across the edge of the knife to sharpen it. Any suitable knife-sharpening apparatus operating in this way may be employed. I have shown, for the purposes of illustration, a particular form of apparatus which forms the subject matter of the above-mentioned co-pending patent 125 application filed by Henry B. Batjer. This apparatus is best shown in Figs. 7 to 10, inclusive, of the drawings. The vertical portion 31^a of the arm 31 carries a guide-block 46 secured in place by a pin or screw 47 and 130

having an extended hub 48 which passes through a recess in the lower end of the arm. Journaled in this hub 48 is a crank shaft 49 carrying a crank 50 and handle 51. Mounted for limited reciprocation on the guide-block 46 is a frame 53 having a tongue and groove connection with the guide-block. The frame 53 has a guide-way 54 in which is mounted for limited vertical reciprocation a frame 55 held in place by the strap 56. On the end of shaft 49 is a cam 52 which rotates within the frames 55 and 53. The frame 55 has a depending arm 59 pivotally connected to a rocking-bar 57 pivotally connected to a central depending enlargement of the frame 53. This rocking-bar lies under the bars 62 and 63 which are carried by blocks 60 pivoted on pins 61 in depending ears of the frame 53, and carrying at their outer ends the supports 65 which may be adjustably clamped by set-screws 67 to the bars 62 and 63, and which carry sharpening stones 66. Coil springs 64 are preferably provided for the purpose of holding the arms 62 and 63 against the engaging surfaces of the rocking-bar 57. It will be observed that with this construction, a rotation of the shaft 49 by means of the handle 51 will turn the cam 52. This will result in moving the sharpening stones 66 from side to side and up and down. The cam is so shaped that the movement has the following sequence, beginning with the parts in the position shown in Fig. 8. In this position, the right-hand stone is elevated, and the left-hand stone is depressed, and the sharpening attachment stands in an intermediate position of its sidewise movement, so that neither stone is in contact with the knife-blade. A rotation of the cam in a counter-clockwise position, as shown in Fig. 8, first moves the frame 53 to the right until the lowered stone 66 comes in contact with the edge of the knife and is pressed against it sufficiently to flex the edge somewhat and effect a good sharpening engagement. Thereupon the sidewise movement of the frame 53 is discontinued and the further rotation of the cam lifts the frame 55 and causes an upward wiping movement of the stone 66 across the edge of the knife. While this sharpening movement of the stone is in progress, the frame 53 stands still, and after the first stone 66 is entirely lifted and the other stone is entirely depressed, further rotation of the cam moves the frame 53 to the left, bringing the now lowered stone into sharpening contact with the other side of the knife edge, whereupon the sidewise movement stops and the second stone is wiped across the edge of the knife while the other stone, out of contact with the knife-edge, is depressed. At the end of this movement the cam comes back to the position shown in Fig. 8.

65 From what has been said, it will be un-

derstood that, although the preferred combination of my invention includes an arrangement by which the sharpener-carrying arm automatically effects the tilting of the knife, and also includes a knife-sharpening apparatus having a pair of sharpening-stones which are alternately wiped across opposite sides of the chopping edge of the knife; nevertheless, the separate elements or sub-combinations of the invention are individually of value and may be used independently of one another. Thus, it is broadly new, so far as I am aware, to tilt the knife with respect to the standard for the purpose of bringing its chopping edge into the above-mentioned advantageous relation to the sharpening-stones, and the appended claims are intended to cover broadly the described mechanism for effecting that result, and its equivalent, whether the tilting mechanism is actuated by the sharpener-carrying arm or otherwise. So, also, the particular mount of the sharpener-carrying arm by means of which it may be given the described downwardly and inwardly sweeping movement may be made use of, whether this movement of the arm affects the tilting or not.

Obviously, the described means for actuating the sharpening-stones is of general application, and it is for this reason that claims for this specific apparatus have been included in a separate application.

I claim:

1. In a fabric-cutting machine, the combination with a standard and a knife adapted to be reciprocated in a straight line, of means for inclining the knife relatively to the standard to extend the lower edge of the knife for sharpening, substantially as described.

2. In a fabric-cutting machine, the combination with a standard having a knife-sheathing groove and a knife carrier supported on the standard and having mechanism for reciprocating the knife in a straight line, of means for tilting the knife-carrier on the standard to project the lower edge of the knife for sharpening, substantially as described.

3. In a motor-driven fabric-cutting machine, the combination with a standard, a motor housing on the standard, and a reciprocating knife driven by the motor and guided by the standard, of a tilting connection between the housing and the standard whereby the housing may be tilted relatively to the standard to extend the lower edge of the knife for sharpening, substantially as described.

4. In a motor-driven fabric-cutting machine, the combination with a standard, a motor housing on the standard, and a reciprocating knife driven by the motor and guided by the standard, of a shaft journaled in the housing, and an eccentric on

the shaft to engage the standard to cause the housing to be tilted relatively to the standard to protrude the lower portion of the knife from the standard for sharpening, 5 substantially as described.

5. In a motor-driven fabric-cutting machine, the combination with a standard, a motor housing on the standard, and a reciprocating knife driven by the motor and 10 guided by the standard, of a shaft having bearings in the housing and in the standard, an eccentric on the shaft working in one of the bearings, and means for rotating the shaft to cause relative movement between the housing and the standard to 15 protrude the knife for sharpening, substantially as described.

6. In a fabric-cutting machine, the combination with a standard, a reciprocating 20 knife and a support and actuating mechanism for the knife, of a device pivoting the support and the standard together, an arm for operating the device to tilt the support relatively to the standard to project the lower end of the knife for 25 sharpening, and a sharpening mechanism carried at the outer end of the arm for sharpening the lower edge of the knife when the same is projected, substantially as 30 described.

7. In a fabric-cutting machine, the combination with a standard, a reciprocating knife and a support and actuating mechanism for the knife, of a device pivoting 35 the support and the standard together, an arm for operating the device to tilt the support relatively to the standard to project the lower end of the knife for sharpening, and a sharpening mechanism carried 40 by the arm and adapted to be brought into operative relation to the lower edge of the knife when the same is projected, substantially as described.

8. In a fabric-cutting machine, the combination with a standard, a reciprocating 45 knife and a support and actuating mechanism for the knife, of a device pivoting the support and the standard together and actuatable to protrude the knife for sharpening, an arm universally jointed to the pivoting device, and a sharpening mechanism carried by the arm, whereby the arm may be given a downward and inward sweep to move the sharpening mechanism 50 from a retracted position into a sharpening position and to simultaneously project the lower end of the knife into sharpening relation with the sharpening stones, substantially as described.

60 9. In a fabric-cutting machine, the combination with a standard, a reciprocating knife and a support and actuating mechanism for the knife, of a device pivoting the support and the standard together and actuatable to protrude the knife for sharpen-

ing, an arm universally jointed to the pivoting device, and a sharpening mechanism carried by the arm and having a pair of sharpening stones and actuating mechanism to wipe the stones alternately across 70 opposite sides of the lower edge of the knife, whereby the arm may be given a downward and inward sweep to move the sharpening mechanism from a retracted position into a sharpening position and to 75 simultaneously project the lower end of the knife into sharpening relation with the sharpening stones, substantially as described.

10. In a fabric-cutting machine, the combination with a standard and a knife-carrier supported thereon, of a tilting shaft coupling the standard and the knife-carrier, an arm mounted upon the shaft for rotation on an axis at an angle to the shaft, and 80 connections whereby the rotation of the arm and the tilting shaft causes a simultaneous rotation of the arm on the said axis to give the outer end of the arm a substantially spiral movement, and a sharpening mechanism carried by the outer end of the arm, substantially as described.

11. In a fabric-cutting machine, the combination with a standard and a knife-carrier supported thereon, of a tilting shaft 95 coupling the standard and the knife-carrier, an arm mounted upon the shaft for rotation on an axis at an angle to the shaft, and connections whereby the rotation of the arm and the tilting shaft causes a simultaneous 100 rotation of the arm on the said axis to give the outer end of the arm a substantially spiral movement, said connection including certain lost motion permitting some rotation of the arm and tilting shaft unaccompanied 105 by rotation of the arm on the said axis, whereby the sharpening mechanism may be swung from a retracted elevated position at one side of the knife support to a lowered sharpening position in line with the knife, 110 and a sharpening mechanism carried by the outer end of the arm, substantially as described.

12. In a fabric-cutting machine, a sharpening attachment, an arm carrying the said attachment and a support for the arm on the machine, said support including two axles, one of which is carried by the other and lies at an angle thereto, and connections whereby the rotation of the arm and one of 115 the axles causes a simultaneous rotation of the arm on the other axle, to impart a substantially spiral movement to the outer end of the arm, substantially as described.

13. In a fabric-cutting machine, a sharpening attachment, an arm carrying the said attachment and support for the arm on the machine, said support including two axles, one of which is carried by the other and lies at an angle thereto, and connections whereby 120 125 130

- the rotation of the arm and one of the axles causes a simultaneous rotation of the arm on the other axle, said connection including a certain lost motion so that some movement of the arm and the said first axle may occur without corresponding movement of the arm on the second axle, whereby the sharpening device may be brought from an elevated retracted position at one side of the machine to a lowered sharpening position in line with the knife to be sharpened, substantially as described.
14. In a fabric-cutting machine, the combination with a standard and a reciprocating knife, of means for inclining the knife relatively to the standard to extend the lower edge of the knife for sharpening, and sharpening means movably mounted on said standard and adapted to be brought into operative relation with the lower edge of the knife when the same is extended, substantially as described.
15. In a fabric-cutting machine, the combination with a standard, having a knife-sheathing groove, and a knife-carrier supported on the standard and having mechanism for reciprocating the knife, of means for tilting the knife-carrier on the standard to project the lower edge of the knife for sharpening, and sharpening means movably mounted on said standard and adapted to be brought into operative relation with the lower edge of the knife when the same is projected.
16. In a motor-driven, fabric-cutting machine, the combination with a standard, a motor housing on the standard, and a reciprocating knife driven by the motor and guided by the standard, of a shaft journalized in the housing, an eccentric on the shaft to engage the standard to cause the housing to be tilted relatively to the standard to protrude the lower portion of the knife from the standard for sharpening, and sharpening means mounted on said shaft and adapted to be brought into position for sharpening the lower edge of the knife when the same has been protruded by movement of the same, substantially as described.
17. In a motor-driven, fabric-cutting machine, the combination with a standard, a motor housing on the standard, and a reciprocating knife driven by the motor and guided by the standard, of a shaft journaled in the housing, an eccentric on the shaft to engage the standard to cause the housing to be tilted relatively to the standard to protrude the lower portion of the knife from the standard for sharpening, and sharpening means mounted on said shaft and adapted to be brought into position for sharpening the lower edge of the knife when the same has been protruded by movement of the same, substantially as described.
18. In a motor-driven, fabric-cutting machine, the combination with a standard, a motor housing on the standard, and a reciprocating knife driven by the motor and guided by the standard, of a shaft having bearings in the housing and in the standard, an eccentric on the shaft working in one of the bearings, means for rotating the shaft to cause relative movement between the housing and the standard to protrude the knife for sharpening, and sharpening means mounted on said shaft and adapted to be brought into position for sharpening the lower edge of the knife when the same has been protruded by movement of the shaft, substantially as described.

In testimony whereof I affix my signature.
HYMAN MAIMIN.
